DESIGN FOR A HAND BAG

Ossip J. Walinsky, New York, N. Y.

Application January 3, 1935, Serial No. 54,696

Term of patent 3½ years

To all whom it may concern:

Be it known that I, Ossip J. Walinsky, a citizen of the United States, and resident of New York city, (Borough of Manhattan), in the county and State of New York, have invented a new, original, and ornamental Design for Handbags, of which the following is a specification, reference being had to the accompanying drawing, forming a part thereof, and of which Figure 1 is an isometric view, and Fig. 2 is a top plan view, and Fig. 3 is an end view of a handbag, showing my new design.

I claim:

The ornamental design for a handbag substantially as shown.

OSSIP J. WALINSKY.
